UNITED STATES PATENT OFFICE.

ERNEST TRAUTMAN, OF LAKWOOD, OHIO, ASSIGNEE TO THE REPUBLIC BOX COMPANY, OF CLEVELAND, OHIO, A CORPORATION OF OHIO.

BOTTLE CRATE.

Application filed May 9, 1927. Serial No. 189,850.

This invention relates to containers, particularly those which are used for holding milk bottles and which are provided with means for enabling the containers to be handled and stored in stacks. Containers of this type usually have longitudinally and transversely extending bars which make compartments, and which also function as reinforcing means to hold the container in shape. Usually such containers are open at the top and bottom and when handled are subjected to considerable abuse.

One form of container construction in use at present has some of the longitudinally extending bars arranged to provide a bottom rest for the bottles. Accordingly, such bars are necessarily near the bottom of the container and are riveted to the end walls on a line parallel to the bottom edge. The end walls are therefore pierced at close intervals, and being considerably weakened will break, if not handled carefully. A container thus damaged is generally considered worthless.

The principal object of the present invention is to make a container which is so reinforced that the end walls will not break off, even though the walls are pierced by rods on a line parallel to and near the bottom. In this connection my invention contemplates the provision of a reinforcing member which may be readily made from sheet metal, and which will have the necessary strength for the purposes desired.

In the drawings, Fig. 1 is a perspective view of a bottle container made in accordance with my invention; Figs. 2 and 3 are sections taken through the container on planes indicated by the correspondingly numbered lines in Fig. 1; and Fig. 4 is a perspective view of a corner reinforcing member which is made in accordance with my invention.

The container illustrated has wooden side walls 10, and end walls 11, which are fastened together by nails in the usual way. The container is divided into compartments by longitudinally extending rods 12 and transversely extending rods 13, the ends of which pass through the end and side walls respectively, and are riveted over to insure a rigid connection. Near the bottom of the container I have shown rods 15, all of which lie in the same horizontal plane and are riveted over on the outer side of each end wall.

To strengthen the container, particularly

at the corners and at the same time to prevent breakage of the end walls, I provide a reinforcing member 20 which extends from the top to the bottom of the container and adjacent each corner thereof. Each reinforcing member comprises a sheet metal angle bar as illustrated in Fig. 4. At the base portion of each member the sides turn outwardly and upwardly to form U-shaped portions 27 and 28 which grip the side and end walls of the container. The top portion of each member is offset inwardly to make an extension 25 which normally projects above the plane of the top of the container and functions to facilitate stacking of the containers in the usual way.

Each reinforcing member is adapted to be fastened at spaced intervals to the side and end walls in any suitable way, such as by rivets 26. Each lowermost rivet extends through the end walls above the horizontal plane, passing through the bottom rest bars 15. Thus the end walls are attached to the reinforcing members above the normal fracture line, and are therefore held securely in place even though the wood should split on a line passing through the plane of the bottom rest bars.

I claim:

1. The combination with a rectangular container open at the top and bottom end, of a reinforcing member within each corner of the container, each member comprising a metallic angular strip having a plurality of U-shaped portions at the bottom thereof, each portion engaging the bottom and outer surface of one of the container walls, and means for fastening the member to the container.

2. The combination with a four-sided container open at the top and bottom, of a plurality of bottom rest bars extending through two of the walls of the container and near the bottom thereof, an angular metallic reinforcing strip within the container and extending from the top to the bottom of the container and adjacent each corner thereof, said strip having portions thereof bent outwardly and upwardly to engage opposite sides of the associated walls, the outer wall engaging portion terminating short of top of the container, and means extending through the outer and inner portions and through the walls for fastening the members to the container.

3. A bottle crate corner reinforcing construction for a rectangular crate, comprising

ing a single piece substantially rectangular sheet metal member longitudinally bent at right angles to fit the inner corner of the crate, said member being inwardly offset at the top to provide a guide for a superimposed crate, the bottom end of the said member being slit along the right angular bend and having the two strips so formed bent into a

U-shape, for embracing the bottom edge of the crate adjacent the corner, and means passing through the legs of each U and the crate material for holding the member in place on the crate. 10

In testimony whereof, I hereunto affix my signature.

ERNEST TRAUTMAN.
